(57) **CLAIM**

The ornamental design for a fresh fruit snack package, as shown and described.

DESCRIPTION

FIG. 1 is a front, top and right perspective view of a fresh fruit snack package showing my new design;

FIG. 2 is a front, bottom and left perspective view thereof;

FIG. 3 is a front elevation view thereof;

FIG. 4 is a top plan view thereof;

FIG. 5 is a rear elevation view thereof;

FIG. 6 is a bottom plan view thereof;

FIG. 7 is a left side view thereof;

FIG. 8 is a right side view thereof;

FIG. 9 is a front, top and right perspective view of an alternate embodiment of FIG. 1;

FIG. 10 is a front, bottom and left perspective view thereof;

FIG. 11 is a front elevation view thereof;

FIG. 12 is a top plan view thereof;

FIG. 13 is a rear elevation view thereof;

FIG. 14 is a bottom plan view thereof;

FIG. 15 is a left side view thereof; and,

FIG. 16 is a right side view thereof.

The broken lines showing in the attached drawings are for illustrative purposes only and form no part of the claimed design.
